PROTECTIVE SYSTEM AND RADIANT ENERGY APPARATUS

William F. Hemler, Washington, D. C.

Application September 10, 1930
Serial No. 481,051

10 Claims. (Cl. 250—34)

The present invention relates to X-ray apparatus utilized for radiography treatment and fluoroscopy, and more particularly to means providing safety to both operator and patient during use thereof.

(1) In the present day apparatus it is customary to ground the various metal portions of the apparatus, such as the X-ray table, the tube stand, etc. for the purpose of preventing injury from shock, should such apparatus accidentally become charged by high tension current in the system. This is satisfactory in installations where the high tension leads are kept out of reach or concealed as in the conventional fluoroscopic apparatus, but it so happens that in most installations, and particularly in the use of radiographic apparatus that there are a number of necessarily exposed high tension wires, e. g. the conductors to and from the tube proper; and should any one accidentally come in contact with such exposed wire and at the same time contact with a grounded metal portion of the apparatus, as is very likely to happen in the case of a patient who inadvertently raises a hand or is getting on or off of the table, or an operator who is changing tube terminals, injury would follow, the current being carried from the conductor to the grounded metal through the patient or operator.

(2) Most floors in X-ray rooms in modern fire-proof buildings are of concrete construction. Such floors are excellent electrical conductors for high tension currents and thus act as uncontrolled grounds to earth for metal equipment standing thereon.

(3) It is customary today to use a 110 volt street current from an ordinary house circuit to operate magnetic breakers in remote control switches, magnetic trips of automatic plate changers, insulated transformers and other low tension electrical devices in rooms where high tension lines are exposed.

Such low tension street lines will ground high tension charges to earth and constitute an uncontrolled ground to earth for high tension charges.

Accordingly, an object of the present invention is to provide means for completely and automatically de-earthing the metal apparatus and all persons approaching thereto when any exposed conductor is charged with high tension current.

In the use of fluoroscopic systems wherein the X-ray tube is usually mounted beneath the surface of the table, and the high tension leads are self contained, i. e. concealed beneath the table

or behind the apparatus, there is little opportunity for anyone to contact directly with such leads as there are none exposed; but there is a greater chance that the metal parts of the apparatus will themselves become charged as the conductors are mounted in close proximity thereto (as distinguished from radiographic and treatment apparatus wherein the high tension leads are usually mounted an appreciable distance from the metal parts, but the tube is supported within easy reach of patient and operator above or in front of the table). Hence it is necessary, for the utmost of safety, that the metal parts be grounded at such time as the fluoroscopic apparatus is being used, and accordingly another object is to provide a means for automatically grounding the system to earth when the fluoroscopic tube is charged.

Frequently, an X-ray installation involves a combination of radiographic, fluoroscopic and treatment apparatus, in order to permit diagnosis as well as therapy; and from the foregoing it will be seen that it is necessary to de-earth the system when radiographic or treatment methods are used which require the presence of exposed high tension lines, and to earth the system when the fluoroscope is used, which permits placing the high tension lines out of probable human reach, the two portions of the system being, of course, operated separately and never simultaneously.

In order to avoid any possible chance of forgetfulness on the part of an operator, means are provided whereby initiation of operation of either phase of the system by means of high tension switches automatically earths or de-earths the apparatus dependent upon whether the exposed conductors or the concealed conductors are charged.

A feature of the system described resides in the means for insulating the entire apparatus from earth by forming walls, floors and ceilings of a heat-proof material, impervious to Roentgen rays and incapable of conducting electricity.

Another feature of the system is the use of a one-one transformer or insulation transformer of other suitable ratio to provide low tension circuits to light cystoscopic lamps, drop lights, to supply magnetic trips for circuit breakers, plate changers, etc.

A more complete disclosure of these and other objects of the invention will appear as the description proceeds, reference being had to the accompanying drawings, in which like reference numerals designate like parts, and of which

Fig. 1 represents a diagrammatic showing in perspective of the apparatus;

Fig. 2 represents an elevation partly in section of the automatic switch for controlling the grounding or ungrounding of the apparatus while controlling the high tension circuits; and

Fig. 3 represents a detail perspective of a portion of the switch.

In the drawings 10 represents a conventional X-ray table having side frames 11. While the X-ray tube may be mounted on a separate, movable standard, preferably, (for the purpose of insuring like potential of all metal objects in the room), the standard 12 is mounted directly on one of the side frames 11. The tube 13 is adjustably supported by the standard 12, and is provided with electrodes 14 connected to high tension leads 15, which are mounted a suitable distance above the table as, for example, by brackets fixed to the ceiling, sufficient flexibility being permitted by conventional reels and flexible wire in the leads to the tube terminals. Beneath the table is located the housing 16 for a fluoroscopic tube (not shown), and into which housing enter the high tension leads 17 therefor.

A switch 18 (shown diagrammatically in Fig. 1) is provided by means of which the high tension current is passed to the leads 15 or 17, as desired, and a foot switch 19 is also provided by means of which the remote control switch for operation of the apparatus for certain uses as in fluoroscopy is controlled.

Current from outside sources for purposes requiring exposed low tension wires which will ordinarily earth high tension charges is fed through leads 20 to an oil insulated transformer 21 of 1-1 ratio, the secondary current from this transformer being thus insulated from earth and utilized for the operation of cystoscopic lamps, drop lights, remote control switches and various other low voltage lamps or apparatus.

This current from outside sources is fed (1) to the primary of the 1-1 transformer and (2) to main X-ray current line of the circuit breaker, and (3) through a special arm of the switch 18 or a separate switch connection therewith for use of various low voltage apparatus. Such apparatus may include a motor or motor driven tilt table (not shown), or as stated above, various lamps, switches, etc. As pointed out hereinafter, the line (3) will be automatically broken when exposed high tension lines are electrified and closed when the unexposed high tension lines are electrified for fluoroscopy.

Similarly, current from outside sources for use in operation of the high tension transformer is fed through the leads 22 which are kept beyond ordinary human reach to an oil insulated circuit breaker 23, this being the main current for X-ray purposes, and carried to a control cabinet for use as primary low tension circuit of the high tension transformer of the system.

The purpose of the current entering through leads 20 is solely for the operation of apparatus requiring low voltage and to this end the secondary of the transformer 21 is carried through the circuit breaker 23, a magnetic switch or circuit breaker operator 23a, thence to the foot switch 19 by means of which the magnetic switch operator is controlled. A circuit 24 in parallel with the circuit through 23 may well operate plate changers or other apparatus in an adjacent room.

The current from leads 22 will pass through the magnetically operated circuit breaker and connections 22a into the X-ray transformer.

An ideal layout comprises a combination radiographic and fluoroscopic room, such as illustrated in Fig. 1 of the drawings, and a separate room for pure radiographic and treatment work, with a control booth and suitable high tension switch and perhaps the main transformer room in between the two. The control booth and the room for radiographic diagnosis are not illustrated here but it is to be understood that suitable apparatus may be located therein. The leads 25 and 26 (Fig. 1) serve to connect the high tension secondary of the main X-ray transformer with the switch 18; lead 24 carries de-earthed low tension circuit from the secondary of the 1-1 transformer to the transformer room.

The side walls and floors of such a laboratory will comprise an electrical insulating medium where heretofore sheet lead and other conducting materials have been used. A plaster having in its composition barium sand and powdered barium and gypsum, to form a medium which is electric-shock proof, ray-proof and fire-proof, is an illustration of such medium and accordingly the walls and floor 27 will be so formed.

By using walls, floors and ceiling of this nature it will be seen that all apparatus is insulated against accidental grounds, and furthermore the 1-1 transformer 21 and the circuit breaker 23 being of the oil insulated type, afford insulation between incoming street leads which might otherwise accidentally serve to ground the high tension charges of the system. The only manner in which any connection to earth is had in that part of the system exposed to ordinary human reach, in the presence of high tension lines as thus far described will be through the main leads from outside, which supply current to the apparatus, and by the use of the oil transformer and oil circuit breaker, such grounding to earth through the low tension street line is prevented.

A purposeful ground 28 to earth is provided and connected through the medium of water pipes or equivalent material embedded in the wall, and a connection therefrom is made to the switch 18.

A ground earthed connection 29 for the table 10 is formed by running a conductor to a terminal 30 of the switch 18. The standard 12 being mounted on or grounded to the frame 11 of the table 10 is likewise earthed through this same connection, and by use of a connection 31 from the switch 19 to the table 10, the earthing of table and all other metal equipment is obtained because all other conducting materials within the exposure room are permanently grounded to the frame of table 10 and frame 11 and thus earthed or de-earthed simultaneously with frame 11. A baffle or protective partition 32 is placed in front of the table 10, or may be attached thereto, this for the purpose of preventing accidental contact with the high tension leads 17, underneath the table; it being understood, of course, that these leads may be suitably encased or embedded in the floor at such points as would otherwise be exposed adjacent to the table.

A casing 33 composed of non-conducting material is arranged between the switch and high tension terminals thereon, and the table 10. By passing the high tension leads from the switch through this casing suitable air insulation is provided, and similarly other leads such as the ground connection 29 or the conductor 24 may be passed as desired through this casing which in effect forms not only a protective enclosure, but an insulator for the high tension leads.

It will thus be seen that a unit potential has

been provided consisting of and secured by the interconnection of all metal apparatus and conducting materials in the rooms, exposed to probable human reach in the proximity of exposed high tension leads, for example, the table 10 with its metal frame 11, the standard 12 for the X-ray tube, and the foot switch 19, and if, for instance, a separate tube stand is used instead of one mounted on the frame 11, such stand is to be included as a part of the unit by firmly grounding same to the table frame by strong cable or in other suitable manner.

The one connection 29 thus serves for the entire unit, and consequently when this connection 15 is completed through the switch 18, the entire apparatus is earthed. When, however, this connection is broken through the switch 18, the entire unit (of exposed conducting material) will be completely de-earthed, inasmuch as the floor 20 and walls of the room are formed of efficient non-conducting or preferably high insulating material, so as to maintain an air distance which is sufficient insulation of the high tension voltages in use.

25 The switch 18 may be of any desirable construction suitable to the purpose, and is illustrated herein as comprising a series of longitudinally extending members 35, which serve to connect and space a series of frame members 36. Certain of 30 these members 36 will mount terminals for certain low voltage lines, as illustrated in Fig. 1, at 37, an illustration being the circuit including the primary 37a of a filament transformer for the X-ray tube, while others support terminal 39 for 35 the line to ground the system to earth as already described, and others for the high tension circuits as illustrated at 38; all so arranged and constructed as to prevent the grounding of the system to earth when exposed high tension lines are 40 in use. Thus at least one of the members 36 will have a terminal 39 effective to establish a ground connection from the conductor 29, and terminal 30, the ground being, as stated above, 45 of any suitable nature as for example, a water pipe embedded in the wall 27.

By reference to Figs. 2 and 3, in which details of such a switch are illustrated, it will be noted that the switch comprises a modification of the usual high tension type commonly used; in this 50 case a rock shaft 40 on which are mounted switch arms 41; a pulley 42 at one end of the shaft is engaged by a control rope 43 which serves as a means to rock the shaft in one direction or another, thereby positioning the switch arms 41 55 against upper or lower terminals supported by the frame members 36. Arms 41 each terminate in a metal contact 44 which engages a terminal adjacent the rock shaft and the arms 41 are effective to connect either the lower terminal or the 60 upper terminal of the frame with the terminal at the rear. Fig. 2 illustrates the frame member at the right of the switch, as shown in Fig. 1.

In the frame member to which the ground terminals are connected, the switch arm 41 when in its lower position will connect terminal 30 directly to terminal 39, and when in its upper position will engage no terminal, but will project free into the air.

70 A suitable arrangement of switch arms is to be used for the low voltage lines, the terminals for which will be mounted on other necessary frames, or on an extension frame or interconnected by cords or cables to other high tension switches as that between the radiographic-treatment and fluoroscopic rooms so that all

metal apparatus in any exposure room connected with the system will necessarily be de-earthed except when the high tension circuit is connected with self contained or non-exposed conductors. It will be obvious that the number 80 of frames, switch arms, and terminals and interconnections of pull cords or arms between switches may be varied as desired to accommodate varying conditions; the main essential of this arrangement being that as the trip cord

43 is pulled in one direction and a circuit established through exposed high tension lines 15, all ground connections to earth will simultaneously be broken, leaving any metal apparatus situated within human reach in any room which may be used completely insulated from the earth; and when the cord is pulled to establish a high tension circuit in the non-exposed or self contained (fluoroscopic) lines 17, all metal apparatus of such fluoroscopic unit will be earthed as a unit through the terminals 30 and 39 (the several elements of the unit having been interconnected by being grounded to the table), it being clear that as the any one set of high tension lines is energized, all others will be 100 de-energized. The high tension switch over the control booth may thus be made to operate as a master high tension and ground switch controlling all high tension and ground circuits.

105 The entire apparatus is electrically insulated from the earth at all times, insofar as ordinary conditions are concerned, due to the construction of walls, floors and ceiling, and the use of the insulation transformer heretofore mentioned; the only possible connection to earth 110 being through the ground 28 via line 29 and terminals 30—39, and when the connection between 30 and 39 is broken, all other possible circuits for high tension currents to earth are likewise broken and there is no possibility or 115 likelihood of accidentally grounding or earthing any part of the apparatus. All leads and conductors, insofar as is possible, are located out of reach of the operator and patient, those through the wall being normally above the average person's reach, those not embedded in the wall being encased by suitable insulation, preferably by providing air distance. The ends of conductors 15 adjacent the tube are necessarily exposed, and when current is passing through 125 these leads, there is no part of the apparatus which can be grounded. The leads 17 are self-contained, concealed and protected and all metal parts are automatically grounded at such time as these leads are electrified.

130 The reason for these conditions will be apparent from the foregoing, viz. when there is a greater chance of the patient or operator contacting with the necessarily exposed high tension leads, and less chance of the apparatus becoming accidentally charged therefrom (as is the case when leads 17 are used), and grounding should be avoided. But when the leads 17 are used, inasmuch as these leads are unexposed, and there is practically no chance of any person coming in contact therewith; and there are then greater chances of accidental charging of the metal apparatus (because of the proximity thereto of such leads), earthing of such apparatus is then necessary.

135 Should there be a failure in the ground line 28, 29, 30, 39 there is still an element of safety provided by the complete insulation of all apparatus from other grounds, even such grounds as might accidentally be provided through the street pri-

mary wires 20 and 22, because in this system such lines are oil insulated from the secondary or insulated low tension circuit which are exposed to high tension conductors, such insulation being sufficient to withstand accidental high tension charges.

It is understood that if other high tension switches or other low tension arms are attached to such switches, they shall be so interconnected as to act simultaneously in order that all grounds to earth shall be broken when exposed high tension leads are charged in any exposure room.

It will be understood that the advantages of the above described system apply regardless of whether a combined radiographic or fluoroscopic apparatus is used, or whether either is used by itself. The insulation of the walls and floors, offers an increased measure of safety and acts to completely insulate either phase of the system. If, however, either part of the system forms the total installation, then of course it may not be necessary to utilize the switch exactly as described. This insulation of floors and walls may be secured:—

(1) By use of barium sand, gypsum, plaster already mentioned as radiation barrier, or

(2) By placing of necessary sheet lead at a distance of preferably 12 inches or a distance at least equal to the spark gap capacity of the transformer in use, below the normal floor level, said distance to be maintained by hollow clay tile, covered by and cemented together by gypsum and other suitable non-conducting cement substances.

Having thus described my invention, what I claim as new and desire to secure by Letters Patent of the United States, is:—

1. In an apparatus of the type described, the combination with metal portions therein, of means to ground said metal portions, and a plurality of X-ray tubes, means to supply high tension current to said tubes including exposed electric conductors to one of said tubes, unexposed conductors to the other of said tubes, said conductors being located in proximity to said metal portions, and means to connect said metal portions to earth when said unexposed conductors are electrified, and to disconnect said metal portions from earth when said exposed conductors are electrified.

2. In an apparatus of the type described, the combination with metal portions therein, of means to ground said metal portions, and a plurality of X-ray tubes, means to supply high tension current to said tubes including exposed electric conductors to one of said tubes, unexposed conductors to the other of said tubes, said conductors being located in proximity to said metal portions, and means including a switch effective to establish simultaneously a circuit through said unexposed conductors when in one position and through said exposed conductors when in another position, and to connect said metal portions to earth through said grounding means, when said unexposed conductors are electrified and to disconnect said metal portions from earth when said exposed conductors are electrified.

3. In an apparatus of the type described, the combination with metal portions therein, of means to ground said metal portions, and an X-ray tube, means to supply high tension current thereto including exposed electric conductors therefor, adjacent certain of said metal portions, and means including a switch effective to establish a circuit through said exposed conductors and simultaneously to disconnect said metal por-

tions from ground when said exposed conductors are electrified, said portions being connected to a terminal of said switch, and said switch having a terminal connected to earth, and an arm effective to complete a circuit through said terminals.

4. In an apparatus of the type described, the combination with metal portions therein, of means to ground said metal portions, and a plurality of X-ray tubes, means to supply high tension current to said tubes including exposed electric conductors to one of said tubes, unexposed conductors to the other of said tubes, said conductors being located in proximity to said metal portions, and means including a switch effective to establish a circuit through said unexposed conductors when in one position and through said exposed conductors when in another position, and simultaneously to connect said metal portions to earth when said unexposed conductors are electrified and to disconnect said metal portions from earth when said exposed conductors are electrified, said portions being connected to a terminal of said switch, and said switch having a terminal connected to earth, and an arm effective to complete a circuit through said terminals.

5. In an apparatus of the type described, the combination with a plurality of metal portions therein, means to ground said metal portions, and an X-ray tube, means to supply high tension current thereto including exposed electric conductors therefor, adjacent certain of said metal portions, means to electrically connect said metal portions to each other thereby to form a unit, means to disconnect said unit from earth when said exposed conductors are electrified, including a switch effective to disconnect said unit from earth and also effective to simultaneously establish a circuit through said exposed conductors.

6. In an apparatus of the class described, having metal portions forming a part thereof, and incoming leads from a source of low voltage current, the combination of an oil insulated transformer to which said leads are electrically connected, an oil insulated circuit breaker electrically connected to said transformer, a plurality of X-ray tubes, means to supply high tension current to said tubes, including an exposed high tension conductor to one of said tubes, an unexposed high tension conductor to the other of said tubes, said conductors being located in proximity to said metal portions, and means to ground said metal portions when said unexposed conductor is electrified, and to disconnect said metal portions from earth when said exposed conductor is electrified.

7. In an apparatus of the class described, having metal portions forming a part thereof, and incoming leads from a source of low voltage current, the combination of an oil insulated transformer to which said leads are electrically connected, an oil insulated circuit breaker electrically connected to said transformer, an X-ray tube, means to supply high tension current thereto including an exposed high tension conductor in proximity to said metal portions and connected in circuit with said circuit breaker, means connected to said transformer for energizing said breaker, and means including a switch effective to establish a circuit through said exposed conductor and to disconnect said metal portions from earth when said exposed conductor is electrified.

8. In an apparatus of the class described hav-

- ing metal portions forming a part thereof, and incoming leads from a source of low voltage current, the combination of an oil insulated transformer to which said leads are electrically connected, an oil insulated circuit breaker electrically connected to said transformer, a plurality of X-ray tubes, means to supply high tension current to said tubes, including an exposed high tension conductor to one of said tubes, an unexposed high tension conductor to the other of said tubes, said conductors being located in proximity to said metal portions, and means, including a switch effective to establish a circuit through said unexposed conductor when in one position, and through said exposed conductor when in another position, to earth said metal portions when said unexposed conductor is electrified and to disconnect said metal portions from earth when said exposed conductor is electrified. 10
- 15 9. In a system of the type described, the combination with conductors leading to a plurality of low voltage electrical devices having metal portions, and a high tension electrical apparatus having metal portions, a source of low voltage current, a transformer, incoming leads connecting said source to said transformer, a plurality of X-ray tubes, means to supply high tension current to said tubes, including an exposed high
- 20 tension conductor to one of said tubes, an unexposed high tension conductor, to the other of said tubes, said conductors being located in proximity to said metal portions, and a switch effective to simultaneously connect said low voltage conductors directly to said source when such unexposed high tension conductors are electrified and to disconnect said low voltage conductors from said source when such unexposed high tension conductors are electrified. 80
- 25 10. In an X-ray, radio-graphic, fluoroscopic system of the type described, the combination of a low tension circuit with a plurality of high tension circuits, one of said high tension circuits being exposed, and another being unexposed, insulating means between said high and low circuits effective to prevent electrification of said low tension circuit by accidental high tension charges from said high tension circuits, a metal electrical device arranged in said low tension circuit and located in proximity to said high tension circuits, and means to connect said device to ground when said unexposed high tension circuit is electrified and to disconnect said device from ground when said exposed high tension circuits 90
- 30 are electrified. 95
